UMBRELLA STRUCTURE

Kenneth T. Norris and Homer E. Rathbun, Los Angeles, Calif.; said Rathbun assignor to said Norris

Application September 18, 1933, Serial No. 689,966

11 Claims. (Cl. 135—28)

A principal object of this invention is to provide a simple, durable and efficient structure capable of being employed in the production of top notches and runners, particularly in a type 5 of collapsible frame such as is shown in our pending application for patent for Umbrella structures, filed July 9, 1932, Serial No. 621,549, of which this is a continuation in part.

An object, also, is to provide a structural form 10 applicable to top notches and runners of an umbrella frame, wherein the top notches and runners are formed of a pair or more parts of sheet metal members suitable secured together, whereby the upper extremities of the bows will be securely hinged to the top notches, the lower extremities of the braces similarly hinged to the runners, the top notches arranged so that they may be supported stationarily on the pole, and the runners slidably held on the pole.

20 Other and more detailed objects of invention will appear as the description progresses.

We have shown a preferred form of our invention in the accompanying drawing, in which:

Fig. 1 is an elevation of an umbrella frame embodying our improvements;

Fig. 2 is an enlarged plan of the same as viewed from the top of the frame;

Fig. 3 is a transverse section of the top notch on line 3—3 of Fig. 2;

Fig. 4 is a sectional plan of the runner on line 4—4 of Fig. 1;

Fig. 5 is a fragmentary section, in elevation, of the runner on line 5—5 of Fig. 1.

An umbrella frame of a type to which our improvements are applicable, as shown in Fig. 1, usually includes a central supporting pole 1, a top notch 2 which is stationarily held on the upper end of the pole, ribs or bows 3 which are hingedly secured to the top notch 2 at their upper ends, a runner 4 which is slidable on the pole 1, and braces 5 which are securely hinged at their lower ends to the runner and at their upper ends to geats 6 which are fixed to the bows 3.

The pole 1 usually has a reduced upper end 7 which provides a shoulder against which the central portion of the top notch 2 abuts, said top notch being suitably secured to the pole for preventing movement thereof on the pole. The top notch is formed of but two sheet metal members 8 and 9 which are concentrically mounted, one upon the other, and permanently secured together, as hereinafter explained.

Member 8 has a central portion 10 with an aperture 11 therein for receiving the end 7 of

the pole 1, and a downwardly and outwardly flaring base portion 12 which is subdivided into a plurality of uniform segments 13, 13, etc. by means of radially disposed slits 14, 14, etc. The outer periphery of member is formed by bending the metal thereof downwardly at 15, and finally inwardly at 16, as shown in Fig. 3, thereby providing a central aperture 17 in the portion 16. Member 9 has a flat body with a central aperture 18, corresponding in size and position to aperture 11, and the periphery thereof is bent upwardly at 19. Members 8 and 9 are correspondingly slotted and they are assembled in such a manner that the inner flat portion of member 9 will be firmly held against the inner surface of the portion 12 of member 8 and the upper surface of the inwardly turned portion 16 of member 8; also the upwardly turned portion 19 of member 9 will nest snugly against the inner surface of the portion 15 of member 8. Thus 10 bearings 20 are formed in each of the segments 12 of member 8 and the corresponding segments of member 9, and the members 8 and 9 are permanently secured together by die forming and assembling the members, as shown.

The flat body portion of member rests upon the shoulder at the bottom of the end 7 of the pole, and a pin 21 may be extended through the end 7 of the pole immediately above the portion 10 of member 8 for preventing the upward movement of the top notch on the pole.

The ribs or bows 3, 3, etc. are securely hinged to the top notch 2 in the following manner: Said bows have upper extremities 22 of flat cross section which carry pintles 23 fixed to the bows at central points and uniformly extended therefrom at opposite sides. The ends 22 of the bows are of a thickness to correspond to the width of and they are adapted to pivotally fit into the slits 14 at the periphery of the top notch 2. The extended ends of the pintles 23 seat in the bearings 20 formed on opposite sides of the slits 14.

The runner 4 comprises three members 24, 25 and 26 which are die formed of sheet metal and die assembled, as in the case of top notch 2, for the purpose of permanently securing the members together. Member 24 is in the form of an elongated cylinder with a central opening therein to slidably fit the pole 1, and has an external downwardly turned flange 28 at its upper extremity, and a pair or more of outwardly projecting lugs 29 which are uniformly spaced downwardly from the flange 28. Members 25 and 26 of the runner 4 correspond, respectively, to the members 8 and 9 of the top notch 2.

Member 25 has an upwardly turned hub portion 30 which snugly fits the exterior of the sleeve 24 and the upper edge of said hub is tightly held between the flange 28 and the body of the sleeve, as shown in Fig. 5. Member 25 is bent outwardly from the hub 30 at 31, thence downwardly at 32 and thence inwardly at 33. Member 26 has its flat inner portion tightly engaging the inner side of portion 31 of member 25 and its periphery similarly engages the inwardly bent portion 33 of member 25, thereby permanently securing the members 25 and 26 together.

The periphery 34 of member 26 is bent upwardly and tightly engages the portion 32 of member 25. Thus bearings are provided in and between the members 25 and 26 to correspond to the bearings 29 in the top notch structure. Members 25 and 26 are subdivided into uniform segments 35, 36, etc. which are formed by radial slits 37, and said slits are adapted to pivotally receive the flattened extremities 38 of the braces 5. Said braces have pintles 39 therein which correspond in form to the pintles 23 of the top notch structure and are similarly hinged to the runner 4 in the bearings on opposite sides of the slits 37.

The lower member 26 of the runner seats upon the upper ends of the lugs 29 of the runner sleeve, in such a manner that the brace holding structure is confined between the flange 28 and the lugs 29, thereby providing a substantially integral runner structure.

It will be observed that we form the top notches and the runners of substantially the same parts, and utilize the same method attaching the bows and braces to said members, respectively. The form of the parts shown is readily adaptable to sheet metal practices and therefore assures economy in manufacturing, rigidity and durability.

What we claim is:

40 1. An umbrella structure including a composite support consisting of a pair of abutting members coaxially arranged, with central portions for engagement with a pole and peripheral attaching segments subdivided by radially disposed slits, the periphery of one of said members being reversely bent and overlapped on the other member to form bearings on opposite sides of said slits, for supporting the frame members of the structure.

50 2. An umbrella structure comprising a support for the frame members of the structure, said support consisting of a pair of coaxially mounted members having central apertures for receiving a pole and flanges therearound with complementary segments separated by radial slits in which ends of certain of the frame members are adapted to pivotally seat, the segments on one of said members being bent over the segments on the other member, for permanently locking the two members together and providing bearings for the pintles of the frame members therebetween.

65 3. In an umbrella structure a support for the frame members of the structure and including a pair of coaxially mounted members having central apertures therein for receiving a pole and flanges outwardly thereof formed with complementary segments separated by radial slits for pivotally receiving certain of the frame members, the segments on one of said members being bent inwardly over the segments of the other member, whereby to lock said last mentioned member within the bends of the first mentioned member and to provide bearings on opposite sides of said slits for the pintles of said frame members.

70 4. In an umbrella structure, a support comprising a pair of complementary sheet metal members

having abutting flat body portions and a plurality of peripheral segments radially extended therefrom and separated by slits, the segments on one of said members having their outer edges bent at right angles to its body portion in the direction of the other member for spacing the mating segments of the two members apart to provide bearings therebetween for the pintles of certain of the frame members, the segments of said other member being bent so as to overlap the outer edges of the segments on the first mentioned member, for permanently securing the two members together.

5 5. An umbrella structure as characterized in claim 1 including a sleeve extending through said abutting members and having a flange at one extremity engaging the central portion of one of said abutting members, and means externally of said sleeve and spaced from said flange for engagement with the other of said abutting members, for locking said abutting members on said sleeve.

20 6. An umbrella structure as characterized in claim 1 including a sleeve extending through the apertures of said abutting members, and means at spaced points on said sleeve for engaging said abutting members, respectively, for locking the abutting members as a unit on said sleeve.

25 7. An umbrella structure as characterized in claim 1 including a sleeve extending through the apertures of said abutting members, a flange on said sleeve and lugs also thereon for engagement, respectively, with said abutting members, whereby to lock the assembled structure together.

30 8. In an umbrella structure a sleeve provided with outwardly bent peripheral abutments in a common horizontal plane, and a pair of abutting frame attaching members telescoping said sleeve, the lowermost of said members being seated on said abutments, the end of said sleeve adjacent the uppermost of said members being formed over the adjacent end of said uppermost member to permanently lock both of said members on said sleeve.

35 9. An umbrella structure as characterized in claim 8 including complementary segments formed on said attaching members and separated by radial slits, the segments of one member being bent over the adjacent sides, edges and the opposite sides of the segments of the other member, to permanently lock said members together.

40 10. In an umbrella structure a sleeve having peripheral abutments thereon, a flange telescoping said sleeve and engaging said abutments, a ring telescoping said sleeve and mating with said flange, said flange and said ring having complementary segments separated by radial slits, the segments on the ring having their outer extremities bent downwardly against outer portions of corresponding flange segments to provide bearings therebetween, said flange segments being bent around the outer edges of said ring to permanently lock the flange and the ring together.

45 11. An umbrella structure including an attaching device formed of two mating members subdivided into a plurality of segments separated by radial slits, the segments of one of said members being bent over the peripheries and underlying the segments of said other member for permanently locking said members together, said members forming bearings adjacent said slits for hingedly supporting the ribs of a frame.
